UNITED STATES PATENT OFFICE.

FRANK G. FEELEY, OF CHICAGO, ILLINOIS, ASSIGNOR TO M. D. KNOWLTON COMPANY,
OF ROCHESTER, NEW YORK, A CORPORATION OF NEW YORK.

MACHINE FOR MAKING BOX-BLANKS.

1,192,407.

Specification of Letters Patent. Patented July 25, 1916.

Application filed February 26, 1915. Serial No. 10,711.

To all whom it may concern:

Be it known that I, FRANK G. FEELEY, a citizen of the United States, and resident of Chicago, in the county of Cook and State 5 of Illinois, have invented certain new and useful Improvements in Machines for Making Box-Blanks, of which the following is a specification.

This invention relates to machines for 10 making box blanks, and particularly to machines for cutting and slotting previously scored or creased blanks or blanks which are subsequently scored or creased.

Machines of this type have been provided 15 in practice with a plurality of slotting knives to cut the transverse slots in the blank to form the flaps, and have also been provided with a cutting or trimming knife disposed adjacent one of the slotting knives and arranged at right angles thereto to trim or 20 cut an edge portion from one of the extreme flaps, thereby reducing the same in length, measuring from its bending crease to the edge of the flap. A similar cutting or trimming knife is sometimes located between two 25 of the intermediate slotting knives, so as to cut a corresponding edge portion from the flap formed by the slotting knives between which the trimming knife is located. The 30 two flaps so trimmed at each side of the blank are those flaps which are folded toward each other when the box is formed from the blank, and the purpose of trimming the flaps in this manner is to cause 35 their edges to meet, but not overlap, as would be the case if the box produced from the blank did not have a square end and two of the mating flaps were not trimmed, as just described.

It is obvious that in a machine of this 40 type, it is often necessary to adjust the slotting knives to vary the distance between the same, so as to produce blanks capable of forming boxes of different shapes. The 45 trimming knife disposed adjacent to and at right angles with the end flap cutting knife will, of course, interfere in no way with such adjustment, and will properly trim the extreme flap of the blank no matter what the

adjustment of the slotting knives may be. 50 The trimming knife arranged between two of the slotting knives for trimming an intermediate flap will, however, prevent adjustment of the two adjacent slotting knives, and when it is desired to change the distance 55 between such slotting knives, it has heretofore been necessary to remove the trimming knife and replace it by a trimming knife of greater or less length, as the case may be, thereby permitting the slotting knives to be 60 located farther apart or closer together. This is obviously an expensive operation and requires considerable time.

It is the object of the present invention to provide trimming means for trimming or 65 reducing the length of an intermediate flap, which trimming means is constructed in the novel manner hereinafter described to permit ready adjustment within certain limits 70 of the slotting knives, between which the trimming means is located.

In furtherance of this and other objects which will hereinafter appear, the invention consists in the novel construction and arrangement of parts hereinafter described. 75

The invention is illustrated in the accompanying drawings, in which:—

Figure 1 is a vertical transverse section through the central portion of a slotting and trimming machine showing the improved mechanism associated therewith for trimming the intermediate flap; Fig. 2 is a front elevation of the central portion of a slotting and trimming machine showing the improved trimming mechanism in front elevation, certain parts being represented in section; Fig. 3 is an enlarged front elevation of the improved trimming mechanism; and Fig. 4 is a plan view showing the two slotting knives, between which the trimming 80 mechanism is located in horizontal section, and also showing certain parts of the improved trimming mechanism arranged between these slotting knives, together with the adjustable die holders which carry the 85 dies that coöperate with the cutting elements.

Referring to the drawings, and particu-

larly to Figs. 1 and 2, the bed of the slotting and trimming machine is shown at 1. Above the bed 1, a knife-bar 2 is mounted to reciprocate in a vertical direction, said 5 knife-bar being actuated from the main shaft 3 of the machine by means of a plurality of eccentrics, one of which is shown at 4, and several links, one of which is shown at 5, said links having at their upper 10 ends, eccentric straps 6 for encircling the eccentric bushings 4 and being connected at their lower ends to the knife-bar 2, as best shown in Fig. 1.

The knife-bar 2 carries a plurality of 15 slotting knives of the type hereinbefore mentioned, only two of the slotting knives being illustrated in the present instance, and being shown at 7 and 8, respectively. These knives are adapted to slot the blank 20 at right angles to the flap-forming crease of the blank to produce an intermediate flap. The other slotting knives not shown in the drawings produce the extreme flaps, and in the event the box has four flaps at 25 either side, they also produce the other intermediate flap, as will be readily understood. The said slotting knives 7 and 8 are mounted in holders 9 and 10, respectively, which are slidably carried by the knife-bar 2, so that said holders 9 and 10 may be 30 adjusted toward or away from each other to vary the distance between the slotting knives.

The slotting knives 7 and 8 coöperate 35 with dies 11 and 12, respectively, carried by the bed of the machine, in suitable die holders 13 and 14. Obviously, the die holders must be adjusted toward or away from each other when the slotting knives 7 and 8 are 40 adjusted toward or away from each other. This is accomplished by making each of the die holders 13 and 14 independently adjustable longitudinally of the machine by mounting each of said die holders on a 45 guide-way 85 formed on the bed of the machine, as best shown in Fig. 1. The lower portions of the die holders 13 and 14 are, of course, so shaped as to coöperate with the guide-way 85. Each of the die holders 50 13 and 14 has journaled therein, a rotatable shaft 15 carrying two pinions 16, a lower segmental portion of which is permitted to project below the die holders through the 55 openings 17 provided therein. Secured to the bed of the machine, under each of the pinions 16, is a stationary rack 18, with each of which one of the pinions 16 coöperates. The shafts 15 extend toward the front 60 of the machine to a point where they may be readily operated by an attendant, and for this purpose, they are each provided with a pin 19 passing therethrough to permit actuation of the shaft by applying a suitable crank thereto. When either of the 65 shafts 15 is turned, the pinions 16 carried

thereby and the stationary racks 18 will cause the die holder, which carries the shaft so turned, to move longitudinally of the machine along the trackway 85. By this means, it is obvious that either or both of the die holders 13 and 14 may be adjusted until they are in proper relation with each other and with the slotting knives 7 and 8. A gib 32 may be provided on each of the die holders 13 and 14 to lock the same in 75 position and before the holders can be adjusted in the manner just described, these gibs must be loosened by means of the bolts 33. When the holders are adjusted, the gibs 32 may be tightened, thereby locking the 80 die holders in place.

The mechanism so far described is adapted to cut two slots at one side of the blank to produce one of the intermediate flaps. In order to trim an edge portion from the 85 flap, and thereby reduce its length in the manner above described, the following means is preferably resorted to. Each of the slotting knives 7 and 8 has arranged at right angles thereto, a relatively short trimming knife, that disposed adjacent to the knife 7 being shown at 20, and the corresponding trimming knife adjacent the slotting knife 8 being shown at 21. These knives are mounted for adjustment transversely of the machine and longitudinally of the knives 7 and 8, in order to produce a flap of the proper length measuring from 90 its bending crease to the edge of the flap. For this purpose, the knives 20 and 21 are 100 mounted on knife holders 22 and 23, respectively, which, in turn, are adjustably carried by the main knife holders 9 and 10 by means of the bolts 24 and 25. By loosening each of these bolts, the holders 22 and 105 23, and hence the knives which they carry, may be adjusted toward and away from the front of the machine to such a position that the trimmed flap will be of the proper length. The relatively short knives 20 and 110 21 just described coöperate with dies 26 and 27, respectively, mounted in the die holders 28 and 29. These die holders also preferably carry dies 30 and 31 to coöperate with the knives 7 and 8, in addition to the dies 115 11 and 12 intended for this purpose.

Obviously the die holders 28 and 29 and the dies 26 and 27 which they carry, must be adjusted on the bed of the machine, in accordance with the adjustment of the knives 120 20 and 21. In order to permit of such adjustment, the holders 28 and 29 are slidably mounted on the holders 13 and 14, respectively, by means of bolts 34 and 35, each having a T-head 36 engaging in a correspondingly shaped recess provided in the holders 28 and 29, as best shown in Figs. 2 and 3. These bolts are normally tightened to lock the holders 28 and 29 to the holders 13 and 14, but are loosened to permit adjust- 130

ment of the holders 28 and 29 with respect to the holders 13 and 14. The position of the holders 28 and 29 is changed by means of a casting 37 having at its upper portion, 5 a recess which is substantially T-shaped in cross section. Each of the die holders 28 and 29 is provided with a depending rear portion, and a T-headed bolt, shown at 38, serves to so connect the die holders 28 and 10 29 with the casting 37 as to permit them to move bodily with the die holders 13 and 14, when the latter are adjusted by means of the racks and pinions 16 and 18, and yet to partake of the movement of the casting 37 when 15 the latter is moved toward and away from the front of the machine to effect adjustment of the die holders 28 and 29, independently of the die holders 13 and 14. The movement of the casting 37, which so adjusts the 20 position of the die holders 28 and 29 transversely of the machine is effected by mounting said casting 37 upon suitable guides, one of which is shown at 39 in Fig. 1. The casting 37 has secured thereto, two forwardly 25 projecting shafts 40, the outer extremal portions of which are toothed as shown at 41, in Fig. 4, to provide racks with which pinions 42 are adapted to coöperate. The pinions 42 are carried by the ends of a stub 30 shaft 43, as best shown in Fig. 3, which, in turn, is mounted in a bracket 44 secured to the bed of the machine. The stub shaft 43 carries at its intermediate portion, a pinion 45 meshing with the pinion 46 carried by an 35 actuating shaft 47, which runs parallel to the front of the machine to a point where it may be conveniently actuated by the attendant. As will be seen from Figs. 2 and 3, this shaft 47 passes through the front portions 40 of die holders 13 and 14. When so actuated, it is obvious that the pinions 42 meshing with the racks 41 will cause longitudinal movement of the latter, and as they are rigidly secured to the casting 37, the said 45 casting will be shifted upon the guides 39. This movement of the casting 37 will be transmitted through the T-headed bolts 38 to the die holders 28 and 29. When the die holders 13 and 14 are adjusted longitudinally of the machine by the racks 18 and the 50 pinions 16, the die holders 28 and 29, which then move with the die holders 13 and 14, simply slide along the casting 37, due to the bolt and slot connection effected by means of the bolt 38. The bolts 38 may be first loosened to permit this adjustment, and when subsequently tightened, aid in locking the parts in adjusted position.

By the construction so far described, it is 55 obvious that if the die holders 13 and 14 are moved toward each other until the dies 26 and 27 come in contact, and if the slotting knives 7 and 8 are adjusted toward each other until the extremities of the relatively 60 short knives 20 and 21 contact, a flap will be formed on the box blank of minimum width measuring between the slots. Furthermore, the knives 20 and 21, in their contacting relation, constitute in effect a continuous trimming knife which will trim the outer 70 edge portion from the flap to reduce its length measuring from its bending crease to the outer edge of the flap.

For flaps of greater width than the combined length of the knives 20 and 21, it is 75 necessary to call into operation, the following trimming mechanism, the cutting elements of which are arranged in alinement with the knives 20 and 21 to continue the cut made in the blank by said knives 20 and 21 when the knives 20 and 21 are not in contacting relation. In other words, when the knives 20 and 21 are separated by adjustment of the slotting knives 7 and 8, and when their coöperating dies on the bed of 80 the machine are separated in accordance therewith, the knives 20 and 21 and coöperating dies will obviously not produce a cut which extends completely across the flap. The intermediate portion of the flap will 85 remain uncut. The trimming mechanism above mentioned to cut the intermediate portion of the flap not cut by the knives 20 and 21 is so designed as to permit adjustment of the knives 7 and 8 and die holders 90 13 and 14, within certain limits without destroying the continuity of the cut across the flap and produced by the knives 20 and 21, the dies coöperating therewith, and the trimming mechanism now to be described. This 95 trimming mechanism preferably comprises a lower movable knife, best shown at 48, and which is arranged in alinement with the relatively short trimming knives 20 and 21 when the parts are in their operative positions. This lower trimming knife 48 is secured to a casting 49, which is gibbed into the casting 37 and adapted to reciprocate in a vertical direction with respect to said casting 37, as clearly shown in Fig. 1. Due to 100 the fact that the casting 49 is gibbed into casting 37, the said casting 49, and hence the knife 48, will be adjusted back and forth with the die holders 28 and 29. The knife 48 is normally held below the dies 26 and 105 27, so as not to interfere with the descent of the knives 20 and 21. The die with which the knife 48 coöperates is shown at 50, and as this is supported above the dies 26 and 27, it is obvious that the knife 48 and die 50 110 may extend all the way from slotting knife 7 to slotting knife 8, under which conditions, a flap of the minimum width would be formed on the blank by the use of the trimming mechanism. As the holders 13 and 14 and slotting knives 7 and 8 may be moved apart until the movable knife 48 of the trimming mechanism and the upper stationary die 50 just fill the space between the relatively 115 short trimming knives 20 and 21, it is ob- 120

125

130

vious that the holders 13 and 14 and slotting knives 7 and 8 may be adjusted away from each other a distance equal to the combined length of the knives 20 and 21, and still have a continuous cut produced across the flap by means of the knives 20 and 21 and the intermediate trimming mechanism comprising the knife 48 and die 50. The knives 7 and 8 and holders 13 and 14 should not, however, be moved far enough apart to cause a gap between the extremities of the knife 48 and die 50 on the one hand, and the relatively short trimming knives 20 and 21 on the other hand, as in this event, the cut across the flap would not be continuous.

In Fig. 4, the holders 13 and 14 and slotting knives 7 and 8 are shown adjusted to such position that the intermediate trimming mechanism comprising the movable knife 48 and die 50 just occupies the space between the ends of the knives 20 and 21. Therefore, the parts are set for cutting a flap of the maximum width by the use of the elements of the trimming mechanism shown. If it is desired to cut a flap of greater width, a longer knife 48 may be employed and a longer coöperating die 50 be substituted.

The stationary die 50 above referred to for coöperation with the movable knife 48 of the intermediate trimming mechanism may be carried by a holder 51, which, in turn, is supported by a bracket 52 projecting rearwardly and slidably mounted in a larger bracket 53, as shown in Figs. 1 and 2. In order to render the bracket 52 slideable in the bracket 53, the latter is provided with guide-ways 54 in which correspondingly shaped guides on the bracket 52 are mounted, and by this means, the bracket 52, and hence the die 50, may be adjusted toward and away from the front of the machine, in accordance with corresponding adjustments of the movable knife 48. Movement of the bracket 52 in the guides 54 may be effected by means of a vertical shaft 55 journaled in the bracket 53 and carrying at its lower end, a spiral gear 55' which meshes with a spiral gear 56. The bracket 52 has mounted therein, a screw shaft 57 which is fixedly carried by said bracket so that it will not turn. The spiral gear 56 has a threaded hub coöperating with the screw 57, so that when said spiral gear 56 is turned, the screw shaft 57, and hence, the bracket 52, in which it is mounted, will be shifted. The turning movements of the shaft 55 to effect this adjustment of the bracket 52 may be produced from an actuating shaft 95 carrying a hand-wheel 96 and meshing beveled gears 97 and 98, carried by the shafts 95 and 55, respectively. Before the adjustment of the bracket 52 can be effected by the above means, it is first necessary to loosen the gib 52' and 53'. When these gib are tightened after adjust-

ment of the bracket 52, they serve to secure the same in place.

Vertical reciprocation of the casting 49 to effect movements of the knife 48 are caused by a link 59 pivotally connected to a shaft 60. The connection between the link 59 and shaft 60 is such, however, as to permit adjustment of the castings 37 and 49 on the guides 39, (Fig. 1), and for this purpose, the lower end of the link 59 is permitted to slide on the shaft 60. The shaft 60 has a bodily up and down movement imparted thereto by means of a rock lever 61 mounted to oscillate about the axis of the shaft 62, which, in turn, is mounted in the brackets 63 (Figs. 1 and 2). By this construction, it is obvious that rocking movements of the lever 61 will effect vertical reciprocation of the casting 49. To impart such rocking movements to the lever 61, two cams are employed which are secured to the main actuating shaft 3 of the machine. These cams are shown at 64 and 65. The cam 65 actuates a cam lever 66 pivoted intermediate its ends, as shown at 67. It is connected at its rear end to a link 68, which, in turn, is pivotally connected to a lever 69 pivoted at one end to the bracket 53, as shown at 70. A link 71, pivotally connected to the intermediate portion of the lever 69, serves to rock the lever 61 about the shaft 62. It will be noted, however, that the cam 65, through the connections just described, is effective only for raising the knife 48, and in order to return the same to its lowermost position, the cam 64 acts upon a cam lever 72 pivoted intermediate its ends, as at 73, and connected by means of a link 74 to rock lever 61. The link 74, however, is connected to the lever 61 at the point 75, so that as the cam lever 72 is actuated by the cam 64, the link 74 will be raised, thereby rocking the lever 61 in such a direction as to lower the casting 49. As the cam 64 serves to lower the knife 48 and the cam 65 serves to raise the same, it is obvious that the dwells and depressions on the cams must be so related that when the dwell of one cam is acting upon the corresponding cam lever, the depression of the other cam must permit its cam lever to remain in its raised position, and vice versa.

In order to properly direct the blanks between the cutting elements, upturned guiding portions 76 are provided on the upper die holder 51 and a sheet-metal guide, shown at 77, serves to support and direct the mid-portion of the blank between the cutting elements. The usual strippers 78 may be located adjacent the slotting knives 7 and 8 to strip the slotted blank from the knives as they ascend.

Before the machine is set in operation, the parts must be set or adjusted to produce a blank according to given specifications, as

follows. The slotting knives 7 and 8 and their coöperating die holders 13 and 14 are adjusted the proper distance apart by means of the shafts 15. The die holders 28 and 29 are then adjusted by turning the shaft 47, and as the movable knife 48 moves with said die holders 28 and 29, this operation properly positions the movable knife 48 and the die holders 28 and 29 to trim the flap to the proper length. The bracket 52 is then advanced by means of the hand-wheel 96 until the upper die 50, which coöperates with the movable knife 48, is slightly in advance of said knife 48. The movable knife 48 is then raised and the bracket 52, carrying the die 50, is moved back until said die 50 makes contact with the movable knife 48. It now remains to properly position the relatively short trimming knives 20 and 21, so that they will properly coöperate with the previously adjusted die holders 28 and 29 and the dies 26 and 27, which they carry. This is accomplished by loosening the bolts which secure the holders 22 and 23 of the knives 20 and 21 to the main knife holders 9 and 10, and then adjusting the position of said holders 22 and 23 until the relatively short trimming knives 20 and 21 assume a position slightly to the rear of the dies 26 and 27. The main knife bar 2 is then lowered, and while in its lowermost position, the relatively short knives 20 and 21 are advanced until they contact with the dies 26 and 27. All the parts are then in proper relation, and in readiness for the machine to be set in operation, it being understood that after the adjustment of each part, the various bolts and gibs which lock the same in place are tightened, in the manner hereinbefore described.

The operation of the parts is so timed that after the machine is set in operation, the movable knife 48 will first rise and coöperate with its die 50 to cut the intermediate portion of the subsequently formed flap. The knife 48 will then descend and will reach its lowermost position before the main knife bar 2 has descended a sufficient distance to cause the slotting knives 7 and 8 to operate upon the blank. While the knife 48 is held in its lowermost position, the knife bar 2, in further descending, will cause the slotting knives 7 and 8 to coöperate with their respective dies 11 and 12 to cut the slots in the blank, and at the same time, the relatively short trimming knives 20 and 21 will coöperate with their respective dies 26 and 27 to complete the cut made by the intermediate trimming knife 48 and its die 50. The knife bar 2 will then be raised and the parts will be in position for a repetition of the operations just described.

Obviously, numerous modifications and changes may be made in the details of construction, as above described, without departing from the spirit or scope of the in-

vention as defined in the accompanying claims.

What I claim is:—

1. In a slotting machine for operating upon box blanks, the combination of two parallel slotting knives for forming a flap on the blank, and trimming mechanism operating between the slotting knives to reduce the length of the flap from the base thereof to its outer edge, said trimming mechanism permitting adjustment of the slotting knives toward and away from each other, for the purpose described.

2. In a slotting machine for operating upon box blanks, the combination of two parallel slotting knives for forming a flap on the blank, and trimming mechanism operating between the slotting knives to reduce the length of the flap from the base thereof to its outer edge, said trimming mechanism being adjustable to produce a flap of the proper length and permitting adjustment of the slotting knives toward and away from each other, for the purpose described.

3. In a slotting machine for operating upon box blanks, the combination of two parallel slotting knives for forming a flap on the blank, and trimming mechanism operating between the slotting knives to reduce the length of the flap from the base thereof to its outer edge, said trimming mechanism being operative to produce a continuous cut across the flap for all adjustments of the slotting knives toward and away from each other within predetermined limits.

4. In a slotting machine for operating upon box blanks, the combination of two parallel slotting knives, and trimming mechanism to reduce the length of the flap made by said slotting knives, comprising one set of cutting elements adapted to cut part way across the flap, and a second set of cutting elements adapted to complete the cut across the flap.

5. In a slotting machine for operating upon box blanks, the combination of two parallel slotting knives, and trimming mechanism to reduce the length of the flap made by said slotting knives, comprising one set of cutting elements arranged at right angles to the slotting knives and adapted to cut part way into the flap from the slots made by said knives, and a second set of cutting elements adapted to complete the cut across the blank.

6. In a slotting machine for operating upon box blanks, the combination with two parallel slotting knives and their coöperating dies, of a trimming knife disposed adjacent the inner side of each of said knives and arranged at right angles thereto, dies to coöperate with said trimming knives, means to adjust each slotting knife and its adjacent trimming knife toward and away from each

other, means to adjust the corresponding dies accordingly, and auxiliary trimming mechanism adapted to complete the cut across the flap when the adjustment of said 5 knives and dies prevents the cut made by the trimming knives from extending completely across the flap.

7. In a slotting machine for operating upon box blanks, the combination with two parallel slotting knives and their coöperating dies, of a trimming knife disposed adjacent the inner side of each of said slotting knives and arranged at right angles thereto, dies to coöperate with said trimming knives, means 10 to adjust each slotting knife and its adjacent trimming knife toward and away from each other, means to adjust the corresponding dies accordingly, means to adjust the trimming knives longitudinally of the slotting knives, means to adjust the trimming knife dies accordingly, and auxiliary trimming mechanism adjustable in accordance 15 with the last-named adjustments of the trimming knives and dies to complete the cut across the flap when the adjustment of said 20 knives and dies toward and away from each other prevents the cut made by the trimming knives from extending completely across the flap.

8. In a slotting machine for operating upon box blanks, the combination of two parallel slotting knives, a trimming knife disposed adjacent to the inner side of each slotting knife and arranged at right angles 35 thereto, dies to coöperate with all of said knives, means to adjust each slotting knife and its trimming knife toward and away from the other slotting and trimming knives, means to adjust the dies accordingly, and 40 auxiliary trimming mechanism operative to complete the cut across the flap made by said trimming knives in various adjustments of said knives and dies toward and away from each other.

9. In a slotting machine for operating upon box blanks, the combination of two parallel slotting knives, a trimming knife disposed adjacent to and arranged at right angles to the inner side of each of said 45 knives, means to adjust the slotting knives toward and away from each other, means to adjust the trimming knives longitudinally of the slotting knives, dies for coöperating with all of said knives, and means to adjust the dies in accordance with the above-named 50 adjustments of the knives.

10. In a slotting machine for operating upon box blanks, the combination with two parallel slotting knives, of trimming mechanism adapted to produce a cut across the flap formed by said slotting knives, and means 55 associated with the slotting knives to complete the cut across the flap made by said trimming mechanism.

11. In a slotting machine for operating

upon box blanks, the combination with two parallel slotting knives, and their coöperating dies, of means to produce a cut across the flap formed by said knives, which cut is at right angles to the slots produced by the 70 slotting knives, said means comprising a movable knife which is operable independently of the two slotting knives.

12. In a slotting machine for operating upon box blanks, the combination with two parallel slotting knives and their coöperating dies, of a trimming knife disposed adjacent the inner side of each of said knives and arranged at right angles thereto, dies to coöperate with said trimming knives, intermediate trimming mechanism for continuing the cut in the blank produced by said trimming knives, means to adjust said trimming knives longitudinally of the slotting knives, means to adjust the trimming knife dies accordingly, and means to adjust said intermediate trimming mechanism in accordance 80 with the adjustments of the trimming knives and their dies.

13. In a slotting machine for operating upon box blanks, the combination of means to produce two parallel slots in the box blank, of means to produce a cut in the blank at right angles to said slots, means to adjust said first-named means to increase the 90 distance between the slots, said second-named means being then inoperative to produce a continuous cut between the slots, and means operable under these conditions to supplement the cut produced by said second-named means and make the same continuous 95 between the slots.

14. In a slotting machine for operating upon box blanks, the combination with two parallel slotting knives, of a trimming knife 105 disposed at the inner side of each of said knives and arranged at right angles thereto, means to adjust said slotting knives toward and away from each other so that when said trimming knives are in abutting relation, a continuous cut may be produced in the blank between said slots, and auxiliary trimming mechanism operable when said trimming knives do not abut to cut that portion of the blank not cut by the trimming knives 110 in order to maintain the continuity of the cut across the flap in various adjustments of the slotting knives.

15. In a slotting machine for operating upon box blanks, the combination with two parallel slotting knives, of a trimming knife 120 disposed at the inner side of each of said knives and arranged at right angles thereto, means to adjust said slotting knives toward and away from each other so that when said trimming knives are in abutting relation, a continuous cut may be produced in the blank between said slots, and auxiliary trimming mechanism operable when said trimming knives do not abut to cut that portion of the 125 blank between said slots, and auxiliary trimming mechanism operable when said trimming knives do not abut to cut that portion of the 130 blank between said slots.

blank not cut by the trimming knives in order to maintain the continuity of the cut across the flap in various adjustments of the slotting knives, said auxiliary trimming mechanism comprising a movable knife operable independently of said slotting knives and the trimming knives carried thereby.

Signed at Chicago, in the county of Cook and State of Illinois, this 23 day of February A. D. 1915.

FRANK G. FEELEY.
